AMUSEMENT DEVICE—COIN CONTROLLED

Iver Ray, Blooming Prairie, Minn.

Application December 26, 1933, Serial No. 703,963

7 Claims. (Cl. 194—71)

My invention relates to amusement devices and particularly to coin controlled devices for showing a series of pictures, articles or the like, wherein the pictures are carried by a rotatable member and rotation of said member is controlled.

Many types of coin controlled amusement devices are in use at the present time, but nearly all of them are of complicated construction and hence are expensive to construct and maintain and are susceptible to many kinds of mechanical failure.

An object of my invention is to provide an amusement device which is simple and inexpensive to construct and yet is efficient and rugged.

Another object is to provide such an amusement device wherein various rows of pictures of a series thereof carried by a rotatable member are successively brought into view by rotation of said rotatable member and wherein rotation of said member is controlled through a predetermined cycle.

Still another object is to provide such a device wherein means is provided to prevent rotation of a rotatable member except following a release effecting operation such as the insertion of a coin and to prevent rotation through more than one revolution following each release effecting operation.

Yet another object is to provide a coin controlled operating mechanism for such an amusement device wherein a deposited coin serves first as an abutment element for actuating a trip lever to release said operating mechanism to permit rotary movement thereof and then is cast into a coin receiving receptacle.

These and other objects and advantages of the present invention will more fully appear from the following description made in connection with the accompanying drawings, wherein like reference characters refer to the same or similar parts throughout the various views, and, in which,

Fig. 1 is a front view of my amusement device;

Fig. 2 is a vertical sectional view taken along the line 2—2 of Fig. 1, as indicated by the arrows;

Fig. 3 is a vertical sectional view taken along the line 3—3 of Fig. 1, as indicated by the arrows;

Fig. 4 is a detail view showing on enlarged scale certain of the parts illustrated in Figs. 2 and 8;

Fig. 5 is a vertical sectional view taken along the line 5—5 of Fig. 3, as indicated by the arrows, and showing certain parts partially broken away;

Fig. 6 is a vertical sectional view taken along the line 6—6 of Fig. 5, as indicated by the arrows, and showing certain parts partially broken away;

Fig. 7 is a horizontal sectional view taken along the line 7—7 of Fig. 5, as indicated by the arrows; and

Fig. 8 is an end view of a picture carrying roll used on the drum of my amusement device.

Referring to the drawings, my amusement device is housed in a cabinet C which includes in its structure a back member 10a, a bottom member 10b, a top member 10c, a side member 10d at the right side, a side member 10e at the left side and a vertical partition 10f. The partition 10f is located to the left of the center of the cabinet C so as to divide the interior of the cabinet into two compartments, the larger of which is toward the right. The top member 10c extends from the rear of the cabinet to a point substantially midway between the front and rear limits of the cabinet. A rail 10g extends a short distance downwardly from the forwardmost portion of the top member 10c. At the front side of the small and large compartments previously described doors 10h and 10j are respectively hingedly connected to the lower edge of the rail 10g and extend downwardly and forwardly therefrom to the forward limit of the cabinet. Doors 10k and 10m, respectively hingedly connected to the side members 10e and 10d and extending vertically from the lower edges of the sloping doors 10h and 10j to the upper side of the bottom member 10b, form the front sides of the small and large compartments. The doors 10k and 10m are provided with locks 10n and 10p for retaining them in closed position. Each of the sloping doors 10h and 10j has secured to the lower portion thereof a plate 10q extending below the lower edge thereof so as to be engaged by one of the vertical doors 10k and 10m to hold the sloping doors 10h and 10j in closed position when the vertical doors 10h and 10j are in closed position. Also stops 10r, secured to the side and partition members 10d, 10e and 10f, are provided to limit closing movement of the sloping doors 10h and 10j.

Certain parts of an amusement device are housed in the larger of the two compartments of the cabinet C and a coin controlled release mechanism included in the amusement device is housed in the smaller compartment. An operating shaft 11 extends through both of the compartments, as shown, and is journalled in suitable apertures in the side and partition members 10d, 10e and 10f. Attached to the right hand end of the shaft ex-

- teriorly of the cabinet C is an operating knob or handwheel 12 for use in rotating the shaft 11.
- A drum D, including centrally apertured disk-shaped end members 13a, longitudinal brace members 13b connecting the end members 13a and a covering 13c extending between and attached to the end members to form the peripheral surface of the drum, is mounted on that portion of the shaft 11 which lies within the larger of the two compartments in the cabinet C. The drum D is retained in a fixed position on the shaft 11 by means of a set-screw 13d disposed in a screw threaded aperture in a boss 13e projecting toward the partition member 13e from the end member 13a nearest the partition 13e. A helical compression spring 13f mounted on the shaft 11 between the drum D and the side member 10d. The covering 13c is formed of relatively stiff sheet material and is proportioned to leave a gap adjacent one of the connecting members 13b and is attached to the end members in such position as to form a lip projecting a short distance from said one of the connecting members 13b toward the gap. A pair of arms 14, connected together at their outer ends by a cross member 14a disposed in the above mentioned gap, are swingably mounted at their inner ends on the shaft 11. The cross member 14a carries a plate 14b which forms a lip projecting toward the previously described lip formed by the covering 13c. A spring 14c is connected between the cross member 14a and one of the connecting members 13b as shown so as to urge the lip carried by the cross member 14a toward the lip formed by the covering 13c.
- A flexible sheet 15, adapted to be stretched about the drum D, has on its outer side a series of rows of pictures and at each end has secured thereto a bar 15a. Each of the bars 15a is cut away to form a lip engaging groove 15b in cooperation with an end portion of the sheet 15 as shown in Fig. 8. The sheet 15 is wrapped about the drum D and is attached thereto by engaging the grooves 15b respectively with the lips formed by the covering 13c and the plate 14b. The spring 14c acts to pull said lips toward each other and hence to retain the flexible sheet 15 on the drum D under tension.
- A viewing window is formed by mounting a transparent plate 16 in a viewing aperture formed in the right hand sloping door 10j. This window is of such size and shape and is so located that one row of the pictures on the flexible sheet 15 will be visible therethrough at a time and, as the drum D is rotated, the various rows of pictures on the sheet 15 will successively be visible.
- The coin controlled release mechanism included in my amusement device is constructed as follows:—
- A ratchet 17 is rigidly mounted on the shaft 11 closely adjacent the side member 10e and within the smaller compartment of the cabinet C. A pawl 18, located to engage the ratchet 17, is swingably mounted on the side member 10e and is urged against the ratchet 17 by a flat spring 18a which is also mounted on the side member 10e. The ratchet 17 and pawl 18 are arranged to freely permit clockwise rotation of the shaft 11 as viewed from the end of the shaft on which the knob 12 is mounted and to limit counter clockwise rotation.
- As best shown in Figs. 3, 5 and 7, a block 19 is rigidly mounted on the shaft 11 approximately intermediate between the side member 10e and the partition 10f. A dog or arm 20, having an offset portion at its free end, is swingably mounted on the block 19 by means of a hinge joint 20a. An L-shaped member 21 is secured to the block 19 and a portion thereof overhangs the arm 20 to limit swinging movement of the arm 20 away from the block 19. Adjacent the hinge joint 20a a trip lever or arm 20b is attached to the arm 20 to extend at substantially right angles therefrom in a direction away from the block 19. A weight 22 is secured to the block 19 at the side opposite the side from which the free end of the arm 20 extends. A stop 23 is secured to the partition member 10f in such a position as to be engaged by the free end of the arm 20 when the shaft 11 is rotated if the arm 20 is in the position thereof nearest the block 19.
- A vertically disposed open topped coin receiving chute 24 is rigidly secured to and extends downwardly from the top member 10c approximately above the shaft 11 and in such position that the lower portion of the chute obstructs the path in which the outer portion of the trip arm 20b travels when the shaft 11 is rotated. The top member 10c is provided with an aperture directly above the top of the coin chute 24 through which coins may be dropped into the chute. The lower end of the coin chute is partially closed to prevent coins from dropping out of the bottom of the chute. The lower portions of the front and back sides and the bottom of the chute are cut away in parts to form a notch 24a through which the outer end of the trip arm 20b may pass. The rear side portion 24b of the coin chute 24 is formed as a piece separate from the remaining parts of the chute and is connected at its upper end to the chute structure so as to be rearwardly swingable away from the main portion of the chute. An L-shaped flat spring 24c is provided to normally maintain the swingable rear portion 24b in position to close the rear of the chute 24.
- Operation*
- Figures 3, 5 and 7 show the coin controlled mechanism in its initial or starting position. If an attempt is made to cause rotation of the shaft 11 in reverse direction from this or any other position the ratchet 17 and pawl 18 will prevent such rotation or at least limit it to rotation through only a slight angle. If an attempt is made to cause forward rotation from the initial position when no coin is situated in the coin chute 24, such rotation will be arrested when the dog or arm 20 strikes the stop 23. If the knob 12 is then released, the eccentrically located weight 22 will cause reverse rotation of the shaft 11 back to its initial or starting position at which time the pawl 18 will strike one of the teeth of the ratchet 17 and prevent further reverse rotation.
- If a coin, such as the coin 25, is disposed in the lower portion of the chute 24, the same will obstruct or block the notch 24a through which the outer end portion of the trip arm 20b would otherwise be free to pass. If forward rotation is started the outer end portion of the trip arm 20b will strike and be restrained from moving through the notch 24a by the coin 25. Continued rotation will result in the trip arm 20b being so tilted with respect to the block 19 that the dog or arm 20 will be swung away from the block 19 and the free end portion of the arm 20 will assume a position wherein it will fail to strike the stop 23 and hence will permit continued rotation of the shaft 11. The spring 24c is of sufficient strength to maintain the rear portion 24b in normal position throughout the above described part

of the operation of my device but when rotation of the shaft 11 has proceeded to a point where the dog 20 has passed the stop 23, the medial portion of the dog 20 strikes the L-shaped member

5 and thus prevents further swinging movement of the dog 20 and the trip arm 20b with respect to the block 19. With further rotation of the shaft 11, the outer portion of the trip arm 20b forces rearward movement of the coin 25 and the rear portion 24b of the chute 24 against the pressure of the spring 24c. As the rear portion 24b moves rearwardly it also moves upwardly and is withdrawn from between the coin 25 and the trip arm 20b whereupon the coin 25 is dropped into

10 the lower portion of the cabinet C which serves as a coin receiving receptacle. The shaft 11 and the picture carrying drum D are free for one revolution of forward rotation. As the one revolution of rotation nears termination, gravity will

15 cause the dog 20 to drop against the block 19 so as to be in position to strike the stop 23 and just after completion of one revolution the dog 20 will strike the stop 23 to prevent further rotation. If the knob 12 is then released the shaft 11 will be

20 reversedly rotated through a slight angle by the weight 22, as was previously described, to again assume its initial or starting position ready for a repetition of the operating cycle described above.

As the shaft 11 and the drum D mounted thereon are rotated it is obvious that the rows of pictures on the flexible sheet 15 carried by the drum D will be successively visible through the transparent plate 16.

It is obvious that a number of similar sheets 35 15 each having thereon a different group of pictures may be provided and that one of these sheets may be readily removed from the drum D and another may be placed on the drum in substitution for the first sheet.

40 It is to be understood that my coin controlled mechanism is readily adapted for use in many types of amusement devices other than the type disclosed, in many types of vending or dispensing machines and in other devices wherein coin controlled operating means are employed.

It is apparent that I have invented a novel, simple, inexpensive, rugged and efficient form of coin controlled amusement device.

45 It will, of course, be understood that various changes may be made in the form, details, arrangement and proportions of the various parts without departing from the scope of the present invention.

What is claimed is:—

55 1. In coin controlled apparatus, an operating shaft for said apparatus, means for rotating said shaft, an arm swingably mounted on said shaft for swinging movement relative to said shaft in a plane normal to said shaft through a limited angle, a portion at the free end of said arm being offset to project a short distance in a direction parallel to the axis of said shaft and said arm being so arranged that swinging thereof will vary the distance between said offset portion and the axis of said shaft, a stationary stop situated so as to be in the path of said offset portion as said shaft is rotated when said arm is at one limit of its swinging movement relative to said shaft and out of the path of said offset portion when said arm is at the other limit of relative movement, a trip lever rigidly secured to said arm and extending outwardly therefrom at an angle thereto and coin receiving means arranged to hold a received coin in position to be struck by said trip lever as rotation of said shaft is started

whereby said trip lever and said arm are so swung that the offset portion of said arm will not strike said stop and said shaft will be free for further rotation.

2. In coin controlled apparatus, an operating shaft for said apparatus, means for turning said shaft through successive cycles of one revolution each, releasable means associated with said shaft for preventing forward rotation thereof beyond rotation from an initial position through a slight angle, said means including a trip arm carried by said shaft for releasing said means to permit further rotation of said shaft and coin receiving means for holding a received coin in the path of said trip arm and adjacent said trip arm when said shaft is in its initial position whereby, when said shaft is rotated forwardly from its initial position through a slight angle, said trip arm will be restrained by said coin from rotation with said shaft and will be swung relative to said shaft to release said releasable means to permit further rotation of said shaft to complete one revolution thereof and thereby return the same to its initial position.

3. In coin controlled apparatus, an operating shaft for said apparatus, releasable means associated with said shaft for preventing rotation thereof, said means including a trip arm carried by said shaft for releasing said means to permit rotation of said shaft, a coin receiving chute having means preventing exit of a coin therefrom through the lower end thereof, the lower end of said chute being located in the path of said trip arm but being notched to permit passage of said trip arm therethrough, the rear side of said chute being swingably mounted for rearward movement, yieldable means for normally maintaining said rear side in position to close the rear of said chute whereby a coin disposed in the lower portion of said chute will prevent passage of said trip arm through said notch when rotation of said shaft is begun and will cause swinging of said trip arm relative to said shaft to release said rotation preventing means.

4. In coin controlled apparatus, an operating shaft for said apparatus, a dog mounted on said shaft for swinging movement through a limited angle relative to said shaft in a plane normal to said shaft, a stationary stop element for engaging said dog when the same is at one limit of said relative movement to prevent rotation of said shaft, an arm rigidly attached to said dog and disposed at an angle thereto, a coin receiving chute having means for preventing a coin from falling out of the lower end thereof, the lower end of said chute being located in the path of the free end of said arm and being notched to permit passage of said free end through said notch, the rear side of said chute being swingably mounted for outward movement, yieldable means for retaining said rear side in its normal position and means restraining said shaft from reverse rotation whereby engagement of said dog with said stop will normally prevent appreciable forward rotation of said shaft beyond a predetermined position and a coin disposed in the lower portion of said chute will close said notch and be struck by the free end of said arm when forward rotation of said arm is begun resulting in said arm and said dog being swung to a position wherein said dog will not strike said stop as rotation of said shaft is continued.

5. In coin controlled apparatus, an operating shaft for said apparatus adapted for forward

rotation from an initial position through a pre-determined cycle, means for rotating said shaft, a trip arm mounted on said shaft in swingable relation thereto, said arm having one portion 5 adapted for engaging stop means and a second portion adapted for engaging a coin, stop means arranged to normally be engaged by said first portion when said shaft has been rotated forwardly through a small part of said cycle to 10 prevent further forward rotation of said shaft, and coin receiving means arranged to hold a received coin in the path of said second portion so that said second portion will strike said coin during rotation of said shaft through said small 15 part of its cycle and said trip arm will be restrained by said coin from rotation with said shaft so as to swing relative to said shaft to avoid said stop means and permit said shaft to rotate through its complete cycle.

20 6. In mechanism for controlling predetermined rotation of a picture or indicia carrying drum, a revolute operating element on which said drum is mounted, releasable means associated with said element for preventing rotation thereof, said means including a swingable trip arm carried by said element for releasing said means to permit rotation of said element, a coin receiving member having means preventing exit of a coin therefrom through the lower end thereof,

25 30. the lower portion of said member being located in the path of said trip arm but being notched to permit passage of said trip arm therethrough, the rear side of said member being mounted to resistingly permit rearward movement thereof

whereby a coin disposed within said member will prevent passage of said trip arm through said notch when rotation of said element is started and will thereby cause swinging of said trip arm relative to said element to release said rotation preventing means.

7. In mechanism for controlling predetermined rotation of a picture or indicia carrying drum, a revolute operating element on which said drum is mounted, releasable means associated with said element for preventing rotation thereof, said means including a trip arm mounted on said element for swinging movement relative thereto between limits and arranged for releasing said means to permit rotation of said element, a coin receiving member having means preventing exit of a coin therefrom through the lower end thereof, the lower portion of said member being in the path of said trip arm but being notched to permit passage of said trip arm therethrough, the rear side of said member being mounted to resistingly permit rearward movement thereof whereby a coin disposed within said member will prevent passage of said trip arm through said notch when rotation of said element is started and will thereby cause swinging of said trip arm relative to said element to release said rotation preventing means and whereby said arm when the same has been swung to one of its limits relative to said element, will rotate with said element to force the rear side of said coin receiving member rearwardly and eject said coin from said coin receiving member.
